UNITED STATES PATENT OFFICE

107,178

DESIGN FOR A PLAYING CARD

Raymond Francis Nekuda, Kansas City, Mo.

Application January 30, 1937, Serial No. 67,353

Term of patent 14 years

To all whom it may concern:

Be it known that I, Raymond Francis Nekuda, a citizen of the United States, residing at Kansas City, in the county of Jackson and State of Missouri, have invented a new, original, and ornamental Design for a Playing Card, of which the following is a specification, reference being had to the accompanying drawing, forming a part thereof.

The figure is a plan view of the back of a playing card showing my new design.

I claim:

The ornamental design for a playing card as shown.

RAYMOND FRANCIS NEKUDA.
